DESIGN FOR A RUG.

SPECIFICATION forming part of Design No. 15,998, dated March 24, 1885.

Application filed January 29, 1885. Term of patent 3½ years.

To all whom it may concern:

Be it known that I, PATRICK McCAFFRAY, a subject of the Queen of Great Britain, residing at Philadelphia, in the county of Philadelphia and State of Pennsylvania, have invented and produced a new and original Design for a Rug; and I do hereby declare that the photographic print accompanying this specification conveys to any one skilled in the art a clear understanding of the same, and is sufficient to enable such person to use my invention.

The leading feature of my design consists in a triple-panel center, the middle panel ornamented by flowers, ornamental borders at top and bottom, with a narrower panel at each end, arched at the top. The end panels are each ornamented with the representation of a bird known as a "stork," the backgrounds show-

ing groups of foliated ornamentation, all as shown in the photographic print accompanying this specification.

What I claim as my invention is—

The design for a rug, as shown, consisting of a triple-panel center, the middle panel ornamented by flowers, ornamental borders at top and bottom, with a narrower panel at each end, arched at the top, the end panels each ornamented with the representation of a bird known as a "stork," the backgrounds showing groups of foliated ornamentation, all as shown and described.
